UNITED STATES PATENT OFFICE.

R. WOSTER KELLAR, OF LA CROSSE, INDIANA.

GAS-ENGINE SPEED CONTROL.

Application filed September 16, 1922. Serial No. 588,675.

To all whom it may concern:

Be it known that I, R. WOSTER KELLAR, a citizen of the United States, residing at La Crosse, in the county of La Porte and 5 State of Indiana, have invented certain new and useful Improvements in Gas-Engine Speed Controls, of which the following is a specification.

My invention relates to improvements in 10 gas engine speed control and it more especially consists of the features hereinafter pointed out in the annexed claims.

The purpose of my invention is to provide 15 a speed control for internal combustion engines, whether such engines are used for stationary purposes or on automobiles, motor boats, airplanes, etc.; that provides positive means for preventing the racing of engines; that also provides means for limiting 20 the maximum speed of engines; and that makes these provisions in such a manner that ordinary inspection will not disclose the location of the control. By reason of these objectives, owners of engines may themselves 25 limit the speed at which the engine can be driven by an attendant, which also permits the owners of fleets of trucks to control the speed of their equipment, thus conserving the life of the trucks and also reducing the 30 wear and tear of the public highways. In addition, State police officials may license motor trucks for certain speeds according to their weight and the load they are intended to carry by installing one of my 35 devices between the carburetor and the engine cylinder and affixing a seal to prevent tampering.

With these and other ends in view, I illustrate in the accompanying drawing such instances of adaptation as will disclose the broad underlying features without limiting myself to the specific details shown thereon or described herein.

Figure 1 is a side elevation of a carburetor 45 and flange attached to an engine cylinder.

Fig. 2 is an enlarged section of the attachment flange disclosing the location of my control device.

Fig. 3 is a front elevation of Fig. 2.

50 Fig. 4 is an elevation of perforate control disks.

In practically carrying out my invention, I may use various alternative expedients according to the exigencies of traffic conditions

etc., without departing from the spirit of 55 my invention.

In the operation of automotive engines, it has been found that fly ball or similar governing means are so easily tampered with that they are of little practical value, but 60 with my device the ultimate or maximum speed of the engine can be definitely controlled so that with the engine throttle wide open a predetermined speed cannot be exceeded. The device is quite invisible and 65 the most careful external inspection will not reveal its presence. It is placed between the flange portion 3 of the manifold 2 and the flange 4 of the carburetor throttle pipe 5. The intake manifold is attached to the cylinder 1 in any well-known manner. The usual throttle 6 is placed between the carburetor 7 and the flanges 3 and 4.

The device is extremely simple. It may 70 consist of two differently formed disks, or 75 of duplicitely formed disks 9. The disks are frictionally secured to each other at their center by pivot pin 12, or any suitable substitute. The disks 9 have a series of 80 concentrically placed openings formed 85 therein, an outer group 18, an inner group 19 and intermediate groups as shown in Fig. 5. The control disks are placed between the gaskets 8 as shown in Fig. 2 so as to control the manifold opening 11 and 90 the carburetor opening 10.

The disks are moved over each other to 95 more or less restrict the free passage of gas through their openings. If one disk is moved sufficiently far over the other one so 100 as to have their openings out of register with each other, the engine would, obviously, be unable to suck in gases from the carburetor. In actual practice, it has been found that the presence of the disks which are adjusted to each other does not hamper the running of the engine at speeds below the maximum for which the disks are set, and when once set the disks require no further attention as they are tightly clamped 105 between the gaskets 8.

The disks 9 permit a more uniform density of fuel flow than disks which have segmental openings, because in the latter there are only two quadrants through which 110 gas can pass at their full opening and these are at isolated portions of the cross section of the fuel passage, while in the case of

Fig. 4 there is a more uniform distribution of the fuel throughout the cross section of the fuel passage. In the broadest sense it is immaterial as to the kind of openings 5 that are formed in the disk or as to the number of the openings, so long as the material remaining between them is sufficiently strong to withstand the suction of the engine, in consequence of which the device is 10 claimed in its broadest scope.

What I claim is:

1. In speed limiting devices, an engine cylinder, a carburetor, a connecting passage therebetween, a throttle in such passage, a thin metallic disk having a plurality of variable sized openings therethrough, another thin metallic disk also having a plurality of similar openings therethrough, means for relatively fixedly securing the 15 disks to each other, and means for securing the assembled disks between the throttle and the engine cylinder.
2. In speed limiting devices, a restricting disk provided with a plurality of openings 20 therethrough arranged concentrically, the

open area of the different concentric groups varying as the diameters of the groups are reduced.

3. In speed limiting devices, a pair of thin metallic disks pivoted to each other one 30 of the said disks having a large number of different sized openings therethrough and the other disk a plurality of similar openings therethrough, and means for clamping the disks in a gas passageway in a sealed-in 35 manner.

4. In speed limiting devices, means for selectively restricting the flow of gas between a carburetor and an engine cylinder comprising a plurality of pivoted-together 40 disks, means embodied in the disks for admitting a predetermined flow of gas through a plurality of openings arranged over the entire area of the disks, and means for holding the adjusted disks against relative displacement between the carburetor and the cylinder. 45

In testimony whereof I affix my signature.

R. WOSTER KELLAR.
